UNITED STATES PATENT OFFICE.

TAKEO TOYAMA, OF NEW YORK, N. Y.

SHOE-FASTENER.

1,371,334.

Specification of Letters Patent. Patented Mar. 15, 1921.

Application filed January 13, 1921. Serial No. 436,911.

To all whom it may concern:

Be it known that I, TAKEO TOYAMA, a citizen of Japan, residing in New York city, county of the Bronx, and State of New 5 York, have invented certain new and useful Improvements in Shoe-Fasteners, of which the following is a clear and exact description, reference being had to the accompanying drawings, forming part of this specification.

10

My invention relates to shoe fasteners and more particularly to such devices as are utilized to secure the uppers of the shoe about the leg above the ankle.

15

My invention has for its objects, among others, to provide an improved arrangement of the lacing, to provide improved securing means for fastening the laces together and to improve the facility of operation and further to provide means for the attachment of jewels, ornamental buttons and the like, whereby the shoe may be ornamented for use upon the stage. Other objects will appear as the description proceeds.

20

In a preferred embodiment of the invention the shoe strings are passed through the lowest eyelets of the shoe from the outside. Each end of the shoe string is brought out of the shoe at the center and it is taken back 30 on the outside of the flap to the next higher eyelet on the same side of the shoe and passed under the flap again to the center. When the ends of the strings are brought out at the center they are inserted through

35

the string supports of the metallic fastener so as to provide two interlocking metallic fasteners at a space intermediate between the eyelets at the center of the shoe. When the strings are loosened the eyelets may be

40

readily interlocked and when the strings are pulled taut at the top and tied in a knot the eyelets secure the flaps together. In order to loosen the flaps and remove the shoe the knot is untied and then the metallic fasteners are separated by breaking it apart, one part from the other.

Reference is made to the drawings for a description of a preferred embodiment of this invention in which like numerals of reference refer to like parts throughout the figures.

Figure 1 is a front view showing a portion of the top of a shoe with the fasteners in place and the leather uppers of the shoe 55 drawn tightly together.

Fig. 2 is a view showing the metallic fas-

teners separated from each other with the string passed through each.

Fig. 3 is a view showing the metallic fasteners carrying the shoe strings secured together in position, and

Fig. 4 is a view of a modification showing how the head of the stud may be used to support any desired type of ornamental head such as a jewel or a mirror.

65

This invention permits the shoe to be fastened and unfastened without the laborious and burdensome operation of running each string through the eyelets every time the shoe is put on or taken off. This is accomplished by securing at a point intermediate the eyelets a metallic fastener adapted to interlock with a metallic fastener carried on the corresponding loop of the string. By the simple operation of tightening the 75 strings the whole may be tightened and put into position very quickly. The fastening device is absolutely secure so that there is no remote danger of accidentally unfastening at any position.

80

Reference is now made to the drawings for a description of the preferred embodiment of my invention. As shown in Fig. 1 the flaps of the uppers of the shoe A and B are provided with eyelets *a* and *b* as is well known in the art. The shoe string is inserted through the two lowermost eyelets of the shoe from the outside, the part 1 of the shoe string on one side and the part 2 of the shoe string on the other side. Both 90 parts 1 and 2 are drawn out toward the center and brought out at the opening between the flaps. On the string 1 a stud 4 is fastened. The stud has a looped metal neck portion 5 which is secured to the metal connecting piece 11 which is integral with two angularly positioned cylindrical grooves 6 and 7. The string 1 is passed through the groove 7 and across the metallic support 11 under the metal neck 5 and through the cylindrical groove 6. From this the string is passed over the flap in the shoe and inserted in the next higher eyelet *a*. String 1 is again brought out, passed through an other metallic fastener and so on to the top. 105

String 2 is passed through the end supports of the interlocking metallic fastener, which is composed of a cylindrical groove 10 and a metallic connecting member formed of spring steel looped about to form the 110 loop 8 with two neck portions normally resiliently placed together, the one of which

is attached to the groove 10 and the other to the cylindrical groove 9. The string 2, it is clear, is passed through the cylindrical groove 10 over and around the cylindrical loop 8 and through the cylindrical groove 9. The string 2 is then brought over the flap of the shoe, inserted through the next higher eyelet and brought back to the opening between the flaps of the shoe where another 10 other metallic fastener similar to the one just described is fastened to the string. This is continued until the top of the shoe is reached so that intermediate the eyelets there is a looped fastener adapted to interlock with the neck 5 of the stud 4 opposite each of the fasteners on the string 1.

In interlocking the metallic fasteners the stud 4 is passed under the cylindrical groove 9 or 10 and the neck 5 is drawn back 20 through the aperture 12. The pull on the stud 4 causes the resilient walls of groove 12 to spread apart so that in locked position the neck 5 lies within the loop 8 and the walls of the groove 12 are placed together resiliently. When all the metallic 25 parts are fastened together the ends 1 and 2 of the shoe laces are pulled taut and the usual knot 3 tied therein at the top.

In unlacing the shoe the knot 3 is loosened 30 so as to loosen each string 1 and 2. Then the string is pulled out a little, starting at the top. The stud 4 is placed back of the groove 12 by passing it under groove 9 or 10 and then is passed through groove 35 12 into the cylindrical loop 8 so as to hold the neck 5 secure.

A modification of the stud fastener is shown in Fig. 4 in which the stud 4^a is provided with a pin which may have the usual groove near its bottom and the neck 40 5^a is modified to permit the pin of the stud 4^a to pass therein and be secured at the bottom by means of a spring or in some manner well known in the art. The advantage 45 of this modification is that any desired ornamentation or design may be carried on the fasteners. For instance the heads of the studs 4^a may be pink jewels or green jewels or small bits of glass or mirrors may 50 be carried so that before the footlights the shoes will give a very pleasing effect.

The metallic fasteners are preferably of tempered steel so that they will withstand the strain received in dancing or similar 55 leg exercises. The metallic parts may be finished in any desired finish known in the art.

Having described a preferred embodiment of my invention it is clear that many 60 modifications may be made in the details thereof without departing from the invention. It is further clear that I have made a substantial improvement in the art of shoe fasteners having provided a very 65 simple and inexpensive shoe fastener that

will result in a saving of literally thousands of hours of labor now extended in lacing and unlacing shoes, particularly those with high flaps or high uppers. I do not therefore wish to limit myself except as in the appended claims.

I claim:

1. An improved fastening device for shoes comprising means for receiving the shoe string on one side of the shoe and adapted to be supported by said string, a stud carried by said means, separate means for receiving the shoe string on the other side of the shoe and adapted to be supported by said string, and means carried by 75 said last-named means for interlocking with said stud.

2. An improved fastening device for shoes comprising angularly positioned grooves for receiving a shoe string, a stud supported between said grooves, two separate grooves for receiving the shoe string on the opposite side of the shoe, said last-named grooves having means connected therewith for interlocking with the stud. 85

3. An improved fastening device for shoes comprising two cylindrical metallic tubes adapted to receive a shoe string and angularly positioned with reference to each other, said cylindrical grooves being connected by means of a third groove adapted to guide the shoe string therebetween and a support carried by said third groove, said support having at its outer extremity a 95 stud mounted thereon. 100

4. An improved fastening device for shoes comprising two cylindrical metallic tubes adapted to receive a shoe string and angularly positioned with reference to each other, said cylindrical grooves being connected by 105 means of a third groove adapted to guide the shoe string therebetween and a support carried by said third groove, said support having at its outer extremity a stud detachably mounted thereon. 110

5. An improved fastening device for shoes comprising two cylindrical angularly positioned grooves adapted to receive a shoe string, said grooves being supported by a connecting link so formed that there is an 115 aperture similar to a neck connecting with an aperture similar to a head and on the outside a groove for the shoe string.

6. An improved fastening device for shoes comprising two angularly positioned cylindrical grooves adapted to receive a shoe string and connected together by means of a piece of metal, a stud supported on said piece of metal by means of a metallic part formed to permit the passage of the shoe 125 string between said metallic part and said support, a separate pair of angularly positioned grooves adapted to receive a shoe string, said grooves being connected together by a piece of metal formed on the 130

- outside to provide a groove and so formed on the inside as to permit said stud to be inserted in a slot between the said angularly positioned grooves and to be received 10
5 in a cylindrical aperture within said slot.
7. An improved fastening device for shoes comprising means adapted to be secured to one part, said means carrying a vertically mounted stud spaced therefrom and means adapted to interlock with said stud comprising a cylindrical loop closed by two resilient parts normally in contact with each other.
- Signed at New York, in the county and State of New York, this 16th day of December, 1920.

TAKEO TOYAMA. [L. s.]
